US00D879071S

(12) **United States Design Patent** (10) **Patent No.:** **US D879,071 S**
(45) **Date of Patent:** **** Mar. 24, 2020**

(54) **LOUDSPEAKER ENCLOSURE**

(71) Applicant: **EVA AUTOMATION, INC.**, Redwood City, CA (US)

(72) Inventors: **Edward Thomas Rose**, London (GB); **Liberty Scarlett Fearn**, London (GB); **Morten Villiers Warren**, London (GB); **Peter Nelson**, San Jose, CA (US); **Bjorn H. Hovland**, Palo Alto, CA (US); **Jason Nims**, Portland, OR (US)

(**) Term: **15 Years**

(21) Appl. No.: **35/504,916**

(22) Filed: **Nov. 10, 2017**

(80) **Hague Agreement Data**

Int. Filing Date: **Nov. 10, 2017**

Int. Reg. No.: **DM/099842**

Int. Reg. Date: **Nov. 10, 2017**

Int. Reg. Pub. Date: **May 11, 2018**

(30) **Foreign Application Priority Data**

May 11, 2017 (GB) 6012277

May 11, 2017 (GB) 6012278

Assistant Examiner — Tracey J Bell

(74) Attorney, Agent, or Firm — Steven Stupp

(57) **CLAIM**

The ornamental design for a loudspeaker enclosure, as shown and described.

DESCRIPTION

9.-10 Loudspeaker enclosures

9.1 : Perspective

9.2 : Front

9.3 : Back

9.4 : Left

9.5 : Right

9.6 : Top

9.7 : Bottom

10.1 : Perspective

10.2 : Perspective

10.3 : Bottom

10.4 : Front

10.5 : Perspective

10.6 : Left

10.7 : Right

10.8 : Perspective

The grayscale shading in reproductions 10.1-10.8 is used only to illustrate the shape of the product and forms no part of the claimed design.

1 Claim, 15 Drawing Sheets
